UNITED STATES PATENT OFFICE.

HANROKU OISHI, OF LOS ANGELES, CALIFORNIA.

SWIMMING APPARATUS.

Application filed August 11, 1925. Serial No. 49,576.

To all whom it may concern:

Be it known that I, HANROKU OISHI, a subject of the Emperor of Japan, residing in the city and county of Los Angeles and 5 State of California, have invented a new and useful Swimming Apparatus, of which the following is a specification.

This invention relates to an improved device adapted to sustain individuals in the 10 water for an emergency or for pleasure, and provided with a manually operated propeller.

The object of the invention is to provide a device of this character which will act as a 15 float to help buoy up the body of the user without any tendency to turn the body over, to provide steering means adapted to be operated by the user, and to provide propelling means therefor, the steering means 20 being actuated by a lever engaging the head and neck of the user, and the propelling means being actuated by the hands of the user.

A further object is to provide deflecting 25 rudders, on opposite sides of the body, whereby the rear of the device may be sustained in relation to the surface of the water to support a light or a heavy person, and to attain a greater ease in propelling the device 30 through the water.

Another object of the invention is to construct the device of such form and material 35 that it is always ready for use, and is efficient as a means for maintaining buoyancy in and propulsion through the water, and capable of gliding through the water with a minimum of friction.

While I have provided simple and efficient 40 means for accomplishing the objects herein specified, it is to be understood that the invention is not limited to the precise construction shown in the drawings, but that minor changes, alterations and modifications, 45 falling within the scope of the appended claims, may be made.

In the drawings, Figure 1 is a side elevation of my improved swimming device. Fig. 2 is a top plan view of the device. Fig. 3 is a longitudinal sectional view of the device. Fig. 4 is a fragmentary detail view 50 of the frame for the working parts, and showing a portion of the propelling mechanism. Fig. 5 is a transverse sectional view 55 of the operative mechanism. Fig. 6 is a perspective detail view of the steering rudder.

Referring more in detail to the drawings, the float 11 is constructed preferably in the form of a fish, and is constructed, preferably of wood, and has inner compartments 12, 80 indicated by dotted lines, and filled with a lighter material 13, such as cork. The rear of the device is formed similar to a boat, and has a rudder 14, for steering purposes, a propeller 15, for propulsion, and tiltable 85 rudders 16, for deflecting the device relative to the surface of the water.

The body of the float 11, is formed of two halves 17 and 18, enclosing the working mechanism, and secured together by a bolt 70 19, extending transversely through the parts 17 and 18. A gasket 20 is interposed between the members 17 and 18.

The working parts are mounted on a frame 21, and consist of the driving shaft 75 22, mounted in the auxiliary frame portion 23, and having mounted thereon, the cranks 24, disposed on opposite sides of the body. A bevel gear wheel 25, fixed to shaft 22, drives the pinion 26 which is fixed to countershaft 27. A gear wheel 28, on shaft 27, drives the combined pinion and gear wheel member 29, on a fixed shaft 30. The member 29, drives a similar member 31 independently operably on shaft 27, and member 31, 85 drives the pinion 32, on the propeller shaft 33. The propeller shaft 33, is journalled in the vertical brace 34, of frame 21, and carries the propeller 15. The train of gears set forth permits the operator, by actuating the 90 cranks 24, to drive the propeller.

The steering lever 35, projects upwardly from the body of the device, and has a forked end 36, adapted to engage with the neck of the operator. Within the body, a 95 transverse brace member 37, has mounted thereon, the pulleys 38, and a bracket member 39, has mounted thereon, the pulleys 40. The rudder 14, is provided at the top with a cross lever 41. Cables 42 and 43, connected at one end to arm 44, of lever 35, and at the opposite end to cross lever 41, pass over pulleys 38 and 40.

The deflecting rudders 16 are fixed to a transverse shaft 45, journalled in the frame 105 portion 46. A lever arm 47, is fixed to shaft 45. An actuating lever 48, pivotally connected at the point 49, has an arm 50 projecting from the body, and adapted to engage with rack teeth 51, along the edge of 110 slot 52, whereby the arm 50 is held in position of adjustment. The opposite arm 53,

of lever 48, is connected by a link 54, with lever arm 47. The tilting of rudders 16 is attained by adjustment of lever 48. Steering lever 35 extends in a transverse slot 55, in the body. A flexible and elastic cover 56, fixed to levers 48 and 35, and at its outer edges to the body, serves to prevent water entering slots 52 and 55.

In use, the device will be beneath and slightly forward relative to the swimmer's body, and has sufficient buoyancy whereby the forward end of the device projects above the surface of the water. The degree of buoyancy is such that the device is not liable to turn over in use. As may be seen, the propeller is actuated upon turning of the cranks by the operator. The operator may, without releasing his hands, steer the device, by turning his head in the direction in which he wishes to turn. This serves to actuate the steering lever, and, through the cable connections with the rudder, to turn the rudder correspondingly.

The effectiveness of the device, relative to buoyancy, is safeguarded by constructing the same of wood and cork, and avoiding any hollow compartments, and the like.

What is claimed is:

1. In a swimming apparatus, the combination with a buoyant body, of propeller mechanism carried thereby, means for manually actuating the propeller mechanism, a shaft extending transversely through the body, deflector rudders mounted on the shaft and disposed on opposite sides of the body, a lever arm integral with the transverse shaft, an actuating lever mounted in the forward portion of the body and projecting upwardly therefrom, and angularly adjustable for tilting the deflector rudders, and a notched sector for maintaining the actuating lever in its adjusted positions, and a link connecting the adjusting lever and said lever arm.

2. In swimming apparatus, the combination with a buoyant body, of propeller mechanism carried thereby, means for manually actuating the propeller mechanism, a rudder mounted at the stern of the body, a tiller lever mounted at the forward end of the body and projecting upwardly therefrom, a bifurcated end on the tiller lever, tiller cables connecting the tiller lever and the rudder, and cable pulleys for said cables arranged whereby the movement of the tiller lever to the right or to the left will actuate the rudder correspondingly.

3. In swimming apparatus, a buoyant body having the greater portion of its buoyant mass at the forward and central portions of the body, a shaft extending trans-

versely through the rear portion of the body, deflector rudders mounted on the shaft and disposed on opposite sides of the body, propeller mechanism carried by the body, means for adjusting the deflector rudders to maintain the body in a floating position in accordance with the speed attained by the propeller mechanism, and means for maintaining the deflector rudder adjusting means in adjusted position.

4. In swimming apparatus, a buoyant body composed of two longitudinal sections, means for securing the halves together, a frame mounted in the body, a propeller mechanism mounted on the frame and within the body, a propeller shaft projecting at the stern of the body, a propeller carried by the propeller shaft, an operating shaft extending transversely through the body and in connection with the propeller mechanism within the body, manually operated cranks on said transverse shaft and disposed on opposite sides of the body, a steering rudder mounted on said frame and at the rear of the body, a tiller lever mounted on said frame and projecting upwardly from the body, a cross lever carried by the rudder and disposed within the body, tiller cables connecting the tiller lever and the cross lever, and cable pulleys for the tiller cables arranged whereby the movement of the tiller lever to the right or to the left will actuate the rudder.

5. In swimming apparatus, a buoyant body having two longitudinal halves, means for securing the halves together, inner recessed portions in the respective halves, a propeller mechanism mounted in the body and disposed in the recessed portions, a propeller shaft extending from the stern portion of the body and in connection with the propeller mechanism, a propeller mounted on the propeller shaft and at the stern portion of the body, said body being composed of solid material, a rudder for the body, a tiller lever projecting from the body, tiller cables within the body and connecting the tiller lever and the rudder, said body having a transversely arranged slot for the tiller lever, deflector rudders disposed at the sides of the body, an actuating lever for the deflector rudders projecting upwardly from the body and through a longitudinal slot in the body, a link member connecting the deflector rudders and actuating lever, and an elastic and flexible cover for said slots.

In testimony whereof, I hereunto affix my signature.

HANROKU OISHI.
